UNITED STATES PATENT OFFICE.

KARL RÖGER, OF BERLIN, GERMANY, ASSIGNOR TO MERGENTHALER LINOTYPE COMPANY, A CORPORATION OF NEW YORK.

TYPOGRAPHICAL COMPOSING AND LINE-CASTING MACHINE.

1,254,279.

Specification of Letters Patent. Patented Jan. 22, 1918.

Application filed June 29, 1914. Serial No. 847,825.

To all whom it may concern:

Be it known that I, KARL RÖGER, a subject of the German Emperor, residing at 33 Teltowerstrasse, Berlin, in the Empire of Germany, have invented new and useful Improvements in Typographical Composing and Line-Casting Machines, of which the following is a specification.

This invention relates to typographical 10 composing and line casting machines of the particular construction in which lines of matrices and expansible wedge space bars are presented in a conveyer or elevator in front of a mold, and after a cast has been 15 made in that mold and against the line of matrices and space bars, the said conveyer conveys the composed line, still comprising the matrices and space bars, directly to the distributing mechanism, without the inter- 20 intermediary of other carriers or conveyers. The composed line is then pushed out of the conveyer into the distributing mechanism and during that operation the space bars are separated from the matrices and descend to 25 their magazine, while the matrices continue on from the distributor to be distributed each into its respective channel, according to the character of the formative cavity thereof.

30 In a line casting machine such as that known commercially under the trade mark "Linotype," there are two devices known respectively as the "first elevator" and the "second elevator," the first elevator serving, 35 as in the present invention, to support the composed line of matrices and space bars during the casting operation, and the second elevator serving to convey the matrices of the composed line, and after the space bars 40 have been separated therefrom, up to the distributing mechanism.

The device which is employed for supporting the composed line in front of the casting mold and afterward conveying the 45 said composed line directly up to the distributing mechanism, is substantially of similar construction as the first elevator of known typographical machines.

The invention has for its object to provide new or improved means whereby the space bars can be separated from the matrices during their journey from the conveyer to the distributing mechanism.

The invention will now be described by

reference to the accompanying drawings, in 55 which—

Figure 1 is a more or less diagrammatic front elevation, showing sufficient of a typographical machine to illustrate the present 60 improvements;

Fig. 2 is an enlarged rear elevation of part of the distributing mechanism, and

Fig. 3 is a part of a transverse section taken on the line 3—3 of Fig. 2.

With reference to Fig. 1, 1 represents the 65 conveyer, which may be substantially of the same construction as that of the before referred to first elevator, this conveyer serving to receive a line of matrices composed from the magazine 2, interspersed with ex- 70 pansible space bars such as that represented in Fig. 3 and hereinafter more particularly described.

After the composed line of matrices and space bars has been received in the head of 75 the conveyer 1, the latter presents it in front of one of the molds 4 which, in well known manner, may be carried in a rotatable mold wheel 5, and when the composed line is then presented to the mold, the latter 80 is filled with metal to form a slug bearing on its front edge a counterpart of the line of characters presented by the matrices of the composed line.

After the slug has been cast as just de- 85 scribed, the conveyer 1 ascends so as to move its head, carrying the composed line, through the path indicated by dotted lines in Fig. 1, and at the end of this travel any of the movable wedges of the space bars not 90 already descended by gravity into their normal positions, abut against a V-shaped bar 6, which is thus caused to positively lower the said wedges and thereby loosen them within the composed line. Immediately 95 after this juncture, the composed line of matrices and space bars is pushed out of the head of the conveyer 1 by a pusher 7 and the matrices, by reason of the toothed combinations with which they are, as well known, provided, engage with a ribbed rail 8, while the space bars, having no such toothed combinations, fail to engage with the rail 8 and descend by gravity to a chute 9 into their respective magazine, which latter is not shown in the accompanying drawings.

The rail 8 leads the matrices suspended

thereon, into the so-called distributor box 10, which is provided with the usual vertically reciprocating finger 11 serving to lift each matrix as it, in turn, takes its place at the 5 head or leading end of the line. The matrices thus raised by the finger 11 are brought into engagement with the well known distributing screws which carry them along the equally well known permuted distributing 10 bar 12, from which the matrices become detached as each arrives over the special channel allotted to it.

The distributing screws are not represented in the drawings, but in Fig. 1 there 15 are shown a few matrices 13 traveling along the distributing rail 12.

To insure the space bars becoming separated from the matrices propelled by the 20 pusher 7, in case there might be a tendency 25 for them to stick to the said matrices, there are preferably provided two cams 14, located immediately over the chute 9, and so arranged that during the progress of the line 30 of matrices and space bars toward the distributor box 10, the lugs 15, Fig. 3, of any 35 space bars which had then not already left the line, engage with the inclined undersurfaces of the cams 14 and are thereby depressed, so that the space bars cannot further 40 remain in the line. The two cams 14, as shown in Fig. 3, are secured one on either side of the distributing rail 8.

In cases in which the chute 9 is not coincident with, or immediately beneath, the receiving 45 end of the distributor rail 8, the space bars are each provided with distributing teeth 16 so that they will themselves become attached to and suspended from the ribbed toothed rail 8, and the ribs of this 50 rail with which those teeth are engaged are cut away, as indicated at 17 in Fig. 2, so that when the space bars arrive at this part of the said rail they become disengaged from it and fall into the chute 9, this disengagement 55 being insured by the cams 14 as previously described in connection with Fig. 1.

The expansible space bars, excepting as regards the before-described teeth 16, are of the usual well known construction, each comprising 60 two permanently connected wedges 18, 19, on the former of which, viz: the wedge 18, the said teeth are formed, and the latter and longer of which is capable of being raised and lowered relatively to the other wedge, so as to increase and decrease 65 respectively its effective thickness in the composed line.

After the composed line of matrices and space bars has been pushed out of the 70 conveyor 1; as previously described, the latter descends to the position in which it receives another line, which may then be in course of composition, and after that, that line is presented to the mold 4 to recommence another 75 cycle of the machine.

The present invention, however, does not concern itself in any way with the composing of the line or the casting of the slug from that line, and it has been introduced into the foregoing description merely as a 70 means of giving a general idea of the cycle of operations, of which the before described distribution constitutes a prominent feature.

Having described my invention, I declare that what I claim and desire to secure by 75 Letters Patent is:—

1. In a typographical machine, the combination of a composed line of matrices and justifying spacers, the latter each being provided with the same distributing combination, a distributor box, a line transporter movable into operative relation to the distributor box, and a longitudinally ribbed rail along which the matrices and spacers are transferred from the transporter to the distributor box, and having a distributing combination to coöperate with those of the spacers and permit their disengagement therefrom. 80

2. In a typographical machine, the combination of a composed line of matrices and justifying spacers, the latter each being provided with the same distributing combination, a distributor box, a line transporter movable into operative relation to the distributor box, and a longitudinally ribbed rail along which the matrices and spacers are transferred from the transporter to the distributor box, and having a distributing combination to coöperate with those of the spacers and permit their disengagement therefrom, a cam piece attached to the rail and adapted to engage the upper ends of the spacers to insure their disengagement therefrom. 90

3. In a typographical machine, the combination of a composed line of matrices and justifying spacers, the latter each being provided with a pair of sustaining teeth, a distributor box, a line transporter movable into operative relation to the distributor box, a longitudinally ribbed rail along which the matrices and spacers are transferred from the transporter to the distributor box, and a conveying chute underlying the ribbed rail, the said ribbed rail having ribs discontinued above the chute to permit the spacers to drop therefrom into the chute during transfer. 100

4. In a typographical composing and line casting machine, the combination with a composed line of matrices and space bars, a distributor box adapted to separate the advancing matrices in succession, a permuted distributor rail receiving the matrices after 115 such separation, a ribbed rail to which the space bars and matrices are attached by means of distributing teeth on those space bars and matrices before they reach the distributor box, a chute beneath this ribbed 120 rail receiving the space bars and matrices before they reach the distributor box, a chute beneath this ribbed 125 rail receiving the space bars and matrices before they reach the distributor box, a chute beneath this ribbed 130 rail receiving the space bars and matrices before they reach the distributor box, a chute beneath this ribbed

5 rail, the ribs of which latter to which the space bars are attached being discontinued over the chute, and cams attached to this ribbed rail also above the chute and adapted to depress the space bars.

10 5. In a typographical machine, the combination of distributing mechanism, a distributor box from which the matrices are fed individually thereto, a ribbed rail leading into the box, and justifying spacers formed with sustaining teeth to engage the rail, the said rail having its ribs cut away at a point in its length to permit the disengagement of the spacers therefrom, in the manner and 15 for the purpose described.

6. In a typographical machine, the com-

bination of distributing mechanism, a distributor box from which the matrices are fed individually thereto, a V-shaped rail extending into the box and having a series 20 of ribs on opposite sides, and a justifying spacer formed with a pair of teeth to engage the upper pair of ribs on the rail, the said upper ribs being cut away at a point in their length to permit the disengagement 25 of the spacer from the ribs.

In witness whereof I have hereunto set my hand in the presence of two witnesses.

KARL RÖGER.
